Patented Sept. 29, 1959

186,210

INFANT'S SHOE

Esther A. Westberg, Highland Park, Ill.

Application February 3, 1958, Serial No. 49,480

Term of patent 14 years

(Cl. D7—7)

Fig. 1 is a right-hand perspective view of the infant's shoe embodying the new design;

Fig. 2 is a left-hand perspective view of the shoe shown in Fig. 1;

Fig. 3 is a top plan view of the shoe shown in Fig. 1;

Fig. 4 is a bottom plan view of the shoe shown in Fig. 1; and

Fig. 5 is a rear elevational view of the shoe shown in Fig. 1.

I claim:

The ornamental design for an infant's shoe, as shown.
